United States Patent Office.

JAMES H. HOLLINGSWORTH, OF PHILADELPHIA, PENNSYLVANIA, ASSIGNOR
TO HIMSELF, ALBERT REMENTER, AND W. C. ROSELL, OF SAME PLACE.

Letters Patent No. 77,980, dated May 19, 1868.

IMPROVED REFRIGERATOR.

The Schedule referred to in these Letters Patent and making part of the same.

TO ALL WHOM IT MAY CONCERN:

Be it known that I, JAMES H. HOLLINGSWORTH, of the city of Philadelphia, in the county of Philadelphia, in the State of Pennsylvania, have invented a new and useful Improvement in "Refrigerators;" and I do hereby declare that the following is a full and exact description of my invention, reference being had to the accompanying drawings, making a part of this specification, in which—

Figure 1 is an elevation view of my refrigerator.

Figure 2 is a sectional elevation of the same.

The object of my invention is to provide a refrigerator of cheap construction, and so contrived that it is kept very cold in all its parts without the use of ice or any chemical cooling or freezing-compound.

To enable others skilled in the art to make and use my invention, I will now proceed to describe its construction and operation.

A is the casing or outside wood (or other suitable material) work of my refrigerator. It may be made cubic, or round, or ornamental, in fact, any shape to suit the taste of the manufacturer and buyer.

B is a box, of tin or any other suitable metal, made so as to fit inside the outside one, A; B being smaller by, say, one-fourth or one-half an inch than box A, the space between the two being filled by plaster, P.

The sides of tin box B go up as high as those of box A, but the top T of B is set some two or three inches lower, so as to allow a recess or space, S P, between top T of box B and cover C of box A.

The side of box B opposite to the doors is so set in as to allow, between the back of box A and back of box B, a space of about one or one and a half inch, for the purpose as hereinafter shown.

Now, on the top of box B, I place a coil of pipes, C P, commencing at the centre and nearly filling up the half space S P between top of B and top of A:

The balance of said space is filled up with common salt, and the coil having been made so as to allow a little space between each coil of pipe, the salt is made to fill up those spaces, so that the pipes are, all along their parcours, entirely surrounded by salt.

The outer end of the coil is brought down in the space between the backs of box B and box A, as shown by dotted lines C' P' in fig. 2, and comes out in O, where a spout, S D, is set.

The starting end E of the coil is made to stand up so as to be in connection with the middle spout or funnel of a water-tank or reservoir, R, which is placed on top of cover C of box A.

The said reservoir is made of tin or any suitable metal, and composed of two metallic boxes, of any shape to suit, inserted, the smaller into the larger, with intermediate space filled, as in the refrigerator itself, with plaster.

Water, W, being poured into R, goes down pipes C P to the egress-cock or spout S D, and can be left there or let out by stopping or opening C D.

Before reaching spout S D, the water has to travel through coil C P, which keeps it a long while in the pipes surrounded with salt, which, being a bad conductor of heat, cools the water, which reaches spout S D always fresh and cold.

The outside of my refrigerator is provided with doors D, in number to suit, and the inside partitioned so as to afford suitable stores for provisions.

It is obvious that the temperature inside is very cold, partly by the non-conductor qualities of the salt on the top, and also the envelope of plaster all round the box B.

A small space, X, is provided on both sides of the coil of pipes, and holes may be bored through the sides of box A, so as to correspond with X, and allow a free current of air to circulate around the coil, if desired.

The pipes I use may be either metallic or gutta percha, India rubber, or any suitable material.

Having thus described my invention, what I claim, and desire to secure by Letters Patent of the United States, is—

Coil of pipes C P and pipes C' P', water-tank W, outer and inside boxes A and B, salt S S, the whole combined and constructed and operating for the purpose and the manner herein described and set forth.

JAMES H. HOLLINGSWORTH. [L. S.]
